The ornamental design for a radio programming memory unit with storage capability, as shown and described.

DESCRIPTION

FIG. 1 is a top front and right side perspective view of a radio programming memory unit with storage capability showing our new design;

FIG. 2 is a left side elevational view thereof;

FIG. 3 is a rear view elevational view thereof; and,

FIG. 4 is a bottom plan view thereof.

The broken lines showing the cord in FIG. 1 are for illustrative purposes only and form no part of the claimed design.

FIG. 1

FIG. 2
